[57] **CLAIM**

The ornamental design for a combination cigar or cigarette holder and divot tool, as shown and described.

DESCRIPTION

FIG. 1 is a top plan view of the combination cigar or cigarette holder and divot tool showing my new design; FIG. 2 is a front elevational view thereof, the rear elevational view being a mirror image thereof;

FIG. 3 is a bottom plan view thereof;

FIG. 4 is a right side elevational view thereof, the left side elevational view being a mirror image thereof; and,

FIG. 5 is a front perspective view thereof;

FIG. 6 is a top plan view of the combination cigar or cigarette holder and divot tool showing a second embodiment of my new design;

FIG. 7 is a front elevational view thereof, the rear elevational view being a mirror image thereof;

FIG. 8 is a bottom plan view thereof;

FIG. 9 is a right side elevational view thereof, the left side elevational view being a mirror image thereof; and,

FIG. 10 is a front perspective view thereof.
